UNITED STATES PATENT OFFICE.

PORTER AMOS MORGAN, OF OKMULGEE, OKLAHOMA.

COMBINATION BURNER.

Application filed June 11, 1921. Serial No. 476,791.

To all whom it may concern:

Be it known that I, PORTER AMOS MORGAN, a citizen of the United States, residing at Okmulgee, in the county of Okmulgee and State of Oklahoma, have invented a new and useful Combination Burner, of which the following is a specification.

This invention relates to fuel burners, the primary object of the invention being to 10 provide a burner which will automatically control the volume of fuel entering the burner tube proportionately to the quantity of air or steam pressure.

A further object of the invention is to 15 provide a burner of this character which may be employed for burning powdered coal, gas, air or oil, suitable means being provided for admitting either of the fuels to the burner tube.

20 With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

25 Referring to the drawings:—

Figure 1 is a longitudinal sectional view through the burner constructed in accordance with the present invention.

Figure 2 is a sectional view taken on line 30 2—2 of Figure 1.

Referring to the drawings in detail, the reference character 5 designates the body portion of the burner which has a threaded opening to accommodate the threaded extremity of the burner tube 6 as clearly shown by Figure 1 of the drawings.

The body portion 5 is also provided with an opening to accommodate the threaded extremity 7 of a pipe adapted to feed powdered coal to the interior of the burner tube, there being provided a suitable valve member 8 for controlling the passage of powdered coal to the burner tube. It will also be understood that when powdered coal is fed to the burner tube, a suitable worm or spiral feeding member is operated in the coal feeding pipe to feed the powdered coal and prevent clogging of the same, within the coal feeding pipe.

55 At the base of the body portion 5 is a gas

or air feeding pipe 9, the passage of gas or air through the pipe, being controlled by the suction caused by the passage of the fuel through the fuel supply tubes, to be hereinafter more fully described. A plug 10 is also threaded in the body portion 5, and as shown, this plug is provided with a threaded bore extending through the central portion thereof and adapted to accommodate the threaded extremity of the pipe 11. A pipe 12 is also threaded in the plug 10 and provides means for connecting the coupling 13 to the plug 10, the coupling 13 being in communication with a high pressure air or steam pipe 14, the passage of air or steam through the pipe being controlled by means of the valve member 15.

Extending into one end of the coupling 13 is a pipe 16 which is closed at its outer end by means of the washer 17 and cap 18, which has a threaded portion operating over the threads of the pipe 16.

Extending through the pipe 11 and disposed in spaced relation therewith, is a tube 19 that has an angularly disposed flange 20 adapted to contact with the end of the pipe 11 to close the end thereof to prevent the passage of air or steam therefrom. This tube 19 has a threaded extremity positioned in the coupling 21, which coupling connects the oil feed pipe 22 to the tube 19, the passage of the oil through the pipe 22 being controlled by means of the valve member 23. A controlling rod indicated at 24 extends through the tube 19 and has its periphery disposed in spaced relation with the inner walls of the tube 19, the outer end of the rod 24 being flared as at 25 to seat on the flanged extremity 20 of the tube 19 to close the tube 19. Due to the construction of the rod and tube 19, it will be seen that an oil passageway is provided therebetween.

A coiled spring indicated at 26 encircles a portion of the tube 19 and has one end 10c thereof contacting with the cap 18, the opposite end abutting the washer 27 which is threaded on the tube 19, the threaded arrangement allowing the tension of the spring 26 to be regulated at the will of the 105 operator. Supported on one end of the controlling rod 24, is a coiled spring 28 which has one end seated on the cap 29 that closes one end of the pipe 30, the coiled spring 28 having its opposite end engag- 110

ing the adjusting nut 31, whereby the tension of the spring 28 may be regulated at the will of the operator.

In the operation of the burner, assuming that the fuel to be burned is powdered coal, the valve members regulating the supply of gas or air, and oil, are closed and the valve member 8 which controls the passage of powdered coal into the burner tube,

10 is open.

The valve member 15 is now operated to admit high pressure air or steam, which air or steam passes to the inner end of the pipe 19, where the same contacts with the flanged extremity 20 of the tube 19 causing the tube to move longitudinally of the pipe 11 and tube 19, permitting the air or steam under pressure to pass therefrom.

It is obvious that as the air and steam 20 pass from the pipe 11, a suction is created which draws the powdered fuel into the burner tube, where the same may be ignited.

If it is desired to use either gas or oil, 25 as a fuel, the pipe feeding powdered coal, is cut off and the valve controlling the passage of the fuel to be used, is opened to admit the fuel to the passageway formed between the tube 19 and rod 24. It is obvious that as the air or steam under pressure passes through the passageway, between the pipe 11 and tube 19, the suction created at the end of the pipe and tube draws the fuel through the tube 19, where the fuel which 35 has mixed with the air or steam is burned. It might be further stated that when the pressure of the air or steam passing into the pipe, is increased or decreased, the spring members 26 and 28 act to automatically adjust or control the movements of 40 the tube 19 and rod 24.

Having thus described the invention, what is claimed as new is:

1. A burner including a body portion, a 45 burner tube in communication with the body portion, a plug having connection with the body portion, a pipe supported by the plug, a tube positioned within the pipe, a control rod in the tube, means for admit-

ting air under pressure to the pipe, means 50 for admitting fuel to the tube 19, said tube adapted to be moved within the pipe by the pressure of air or steam passing through the pipe, said controlling rod adapted to move to control the passage of 55 fuel through the tube, and coiled springs for returning the tube and rod to their normal positions.

2. In a burner, a burner tube, a pipe positioned in the burner tube, a tube in the pipe and disposed in spaced relation therewith to provide a passageway, means for admitting air under pressure to the passageway, a rod in the tube, said tube and rod adapted to move to exhaust fuel from 65 one end thereof, and coiled springs for regulating the movements of the tube and rod.

3. In a burner, a burner tube, an air supply pipe disposed within the burner tube, 70 a fuel supply tube disposed within the air supply pipe, said fuel supply tube having a flanged extremity contacting with one end of the air supply pipes to close the same, a controlling rod operating within the fuel supply tube and having a flared extremity, 75 contacting with the flanged extremity of the oil supply tube for controlling the passage of fuel through the tube, and spring members for returning the tube and rod to 80 their normal positions.

4. In a burner, a burner tube, an air supply pipe disposed within the burner tube, a fuel supplying tube supported within the air supply pipe, a rod for controlling the 85 passage of fuel to the burner tube, a coiled spring positioned on the tube and adapted to normally move the tube in one direction, means for regulating the tension of the spring, and means for regulating the supply of air to the air supply pipe.

In testimony that I claim the foregoing as my own, I have hereto affixed my signature in the presence of two witnesses.

PORTER AMOS MORGAN.

Witnesses:

H. RAYMOND MYERS,

J. F. A. DECK.
